BLOTTING ATTACHMENT FOR FOUNTAIN PENS

Atwood R. Knorr, Berwick, Pa.

Application May 8, 1935, Serial No. 20,462

5 Claims. (Cl. 120—26)

This invention relates to a blotting attachment for fountain pens.

The primary object of the invention is to form the closure cap of a fountain pen with a rotatable drum that carries a roll of blotting paper which may be projected or retracted by merely turning the drum.

Another feature of the present invention is to provide a door in the side of the closure cap which opens and closes at predetermined times in response to the movement of the drum so that the door will open and allow the blotter to be extended and to close when the blotter has been retracted within the cap.

Another feature of the present invention is to provide an absorbing pad on one end of the drum that has a wiping engagement with the writing end of the barrel of the fountain pen so that the writing end may be cleaned of ink.

With the foregoing and other objects in view the invention consists of a novel construction, combination and arrangement of parts as will be hereinafter more specifically described and illustrated in the accompanying drawing wherein is disclosed an embodiment of the invention, but it is to be understood that changes, variations and modifications may be resorted to without departing from the spirit of the claims hereunto appended.

In the drawing wherein like reference characters denote corresponding parts throughout the several views:

Figure 1 is a fragmentary elevation of the writing end of the barrel of a fountain pen showing the cap in accordance with the present invention applied thereto which cap is shown in a detailed axial sectional view.

Figure 2 is a detailed diametric section through the cap taken substantially on the line 2—2 of Figure 1 and looking in the direction of the arrows.

Figure 3 is a perspective view of the drum removed from the cap.

Figure 4 is a perspective view of the door.

Figure 5 is a fragmentary elevation of the lower end of the drum.

Referring to the drawing in detail, A indicates the barrel of a fountain pen of the conventional structure formed with a smooth writing end 6 from which projects the writing nib 7. Adjacent the smooth end are screw threads 8 by which the cap is attached to the writing end of the pen. This construction of the barrel of the fountain pen is conventional in the art and the cap in accordance with the present invention is made to

conform to the conventional barrels of fountain pens.

The cap constructed in accordance with the present invention is indicated at B and is made of a sleeve 9 the walls of which are thickened adjacent the lower end. An intermediate portion of the thickened walls is threaded as at 10 to receive the threads 8 on the barrel of the fountain pen when the cap is over the writing end of the pen. Adjacent the threads 10 is a smoothed tapered portion 11 on the inner end of the sleeve which frictionally engages the blunt end of the barrel when the pen is being used for writing. The outer end of the sleeve 9 is open. Above the thick walls sleeve 9 has an interior race 23a formed around the inside to rotatably receive the bead on the socket as will appear later. Between the open end of sleeve 9 and the thickened lower end thereof is an elongated opening 12 and the walls about the opening are tapered. For closing the elongated opening 12 there is a door 13 having the edges thereof tapering to conformably fit in the tapering walls of the opening so that the door will open inwardly as shown in dotted lines in Figure 2 of the drawing.

Adjacent the upper end of the opening 12 on the inside of the sleeve 9 is secured a hinge sleeve 14 that receives an inset trunnion 15 anchored to the upper end of the door 13. Anchored to the lower end of the door is a wire member of flexible nature indicated at C. This wire member has a right angled extension 16 adjacent the lower end of the door which merges in a larger angular extension 17 that in turn terminates in a lip 18. The first angular extension 16 forms a trunnion that is journaled in a hinge sleeve 19 secured inside the sleeve 9 adjacent the lower end of the door opening 12. The second angular extension 17 projects outwardly into the chamber of sleeve 9 while the lip 18 bears on the inside of the sleeve all of which is clearly shown in Figure 2 of the drawing.

The letter D indicates a hollow metal drum which is partly confined in the sleeve 9. An intermediate portion of the drum D is reduced to provide a cylindrical spool 20 on which is wound the strip of blotting paper 21. Next to the spool 20 at the inner end of the drum is an outset socket 22 and this socket has an outset bead 23 on its free end. The bead is radially split at circumferentially spaced intervals as at 24 to permit the bead to be flexed to change the annular pad 25 detachably mounted in the socket 22. Bead 23 rides in annular race 23a and is flexed into 55

and out of the race by pulling or pushing on the drum D. The center of pad 25 has a round opening 26 which has a wiping abutment with the writing end 6 of the barrel so as to free the writing end of ink as the barrel is inserted and removed from the chamber 27 of the drum.

In the outer face of the socket 22 is a segmental pocket or cavity 28 which extends from the bead 23 inwardly a portion of the width of the socket. Adjacent the outer end of the socket there are screw threads fashioned in a spiral manner and these screw threads are indicated at 29. The inner end of the screw threads terminate as at 30 in the cavity 28. The outer end 15 of the drum D is formed with a cylindrical knob 31 which merges with an inset shoulder 32. The knob 31 forms a closure for the outer end of the sleeve 9, the shoulder 32 slidably and rotatably engaging with the inner face of the sleeve at 20 the outer end thereof. Adjacent the shoulder 32 the drum is formed with an inset shoulder 33 stepped relative to the shoulder 32 and this shoulder 33 merges with the outer end of spool 20. A wire blotter support 34 bridges the spool 25 20 having the upper end of the wire hinged to the shoulder 33 as at 35. The inner end of wire 34 extends into an opening in the socket 22 as at 36. By flexing an intermediate portion of the wire 34 the free end may be disengaged from the 30 opening in the socket so that the strip blotter may be replenished when desired. The inner end of the blotter is looped around the wire 34 as at 37 so that when the drum D is turned by the knob 31 the blotter is extended from or retracted into the sleeve 9. When the blotter 21 is wound on the spool 20 the free end 38 of the blotter is disposed adjacent the door 13, on the inside of the sleeve 9. In the closed position, the apex of the angular portion 17 is seated in the 40 cavity 28. To project the blotter 21 for use the knob 31 is turned in a counterclockwise direction with respect to Figure 2 of the drawing. This movement results in moving member 17 out of cavity 28 with the apex tracking in the terminal 30 of the thread and further movement will cause the apex to ride in the thread as the knob is turned further. When member 17 tracks in the thread it flexes to the dotted line position shown in Figure 2 of the drawing which results 50 in opening the door 13 inwardly. When the end 38 of the blotter 21 reaches the opening the door forms an abutment to train the free end of the blotter through the opening and further turning of the knob causes the strip of blotting paper to 55 be projected further to a length as desired. To retract the blotter, the knob is turned in the opposite direction which movement will continue until the end 38 of the blotter is on the inside

of the sleeve 9 when member 17 drops from terminal 30 of the thread into the cavity 28 which action closes the door 13.

Having thus described the invention, what is claimed as new is:

1. The combination with a fountain pen cap of a rotatable drum mounted in the cap, a door carried by the cap, a blotter rolled on the drum, and means coacting with the drum for controlling the opening and closing of the door in response to the movement of the drum.

2. The combination with a fountain pen cap of a rotatable drum mounted in the cap, a door swingingly mounted on the cap, a blotter rolled on the drum, means coacting with the drum for controlling the opening and closing of the door in response to the movement of the drum, and means on one end of the drum forming a closure for the cap.

3. The combination with a fountain pen cap of a rotatable drum mounted in the cap, a door in the cap, a blotter rolled on the drum, means coacting with the drum for controlling the opening and closing of the door in response to the movement of the drum, means on one end of the drum forming a closure for the cap, a socket formed on the other end of the drum, and a ring of absorbing material carried by the socket for wiping the barrel of a fountain pen as the cap is transposed from one end of the barrel to the other.

4. The combination with a fountain pen cap including an interior race of a rotatable drum mounted in the cap, a door in the cap, a blotter rolled on the drum, means for controlling the opening and closing of the door, means on one end of the drum forming a closure for the cap, a socket formed on the other end of the drum, a ring of absorbing material carried by the socket for cleaning the barrel of a fountain pen as the cap is transposed from one end of the barrel to the other, said socket formed with a bead on the edge coacting with the annular race in the cap so that when a renewal of either the blotter or absorbing pad is desired the drum may be removed from and again inserted in the cap quickly and easily.

5. A fountain pen cap of the character that is adapted to be mounted on and fit over either end of a fountain pen, a drum rotatably mounted in the cap and into which the writing end of the pen extends when the cap is mounted on the writing end of the pen and an ink absorbent member carried by the drum whereby the writing end of the pen is wiped free of ink.
